[57] CLAIM

The ornamental design for a barbecue grille scraper head, as shown and described.

DESCRIPTION

FIG. 1 is a bottom view, partly in phantom as to the handle portion thereof, showing the barbecue grille scraper head of my new design;

FIG. 2 is a front view thereof;

FIG. 3 is a right side view thereof, partly in phantom as to the handle portion thereof;

FIG. 4 is a rear view thereof, partly in phantom as to the handle portion thereof;

FIG. 5 is a left hand front perspective view thereof taken as to the bottom of the barbecue grille scraper head of FIG. 1, partly in phantom as to the handle portion thereof; and,

FIG. 6 is a left hand rear perspective view, taken as to the top of the barbecue grille scraper head of FIG. 1, partly in phantom as to the handle portion thereof.

The broken line showing of the handle in FIG. 1, 3, 4, 5 and 6 is for illustrative purposes only and forms no part of the claimed design.
